UNITED STATES PATENT OFFICE.

WILLIAM H. SHERMAN AND JOHN F. McGINNITEY, OF ST. JOSEPH, MISSOURI.

BARREL-HEAD.

1,249,217.

Specification of Letters Patent.

Patented Dec. 4, 1917.

Application filed October 31, 1916. Serial No. 128,777.

To all whom it may concern:

Be it known that we, WILLIAM H. SHERMAN and JOHN F. McGINNITEY, citizens of the United States, residing at St. Joseph, in 5 the county of Buchanan and State of Missouri, have invented certain new and useful Improvements in Barrel-Heads, of which the following is a specification.

The invention relates to barrel heads, and 10 more particularly to the class of self-locking barrel heads.

The primary object of the invention is the provision of a head of this character wherein the end of the barrel receiving the head is materially reinforced and said barrel can be opened by the removal of the head, thereby increasing the life of the barrel for 15 use.

Another object of the invention is the provision of a head of this character wherein access can be had to the interior of the barrel with despatch without damage to the barrel or the head, thereby rendering the barrel practically indestructible and in event that 20 the barrel becomes unfit for use the head can be removed and placed within a new barrel, so that both the barrel and the head will have maximum wearing quality and also will minimize labor in the opening or closing 25 of the barrel when the same is used for the shipment of contents from one point to another.

A further object of the invention is the provision of a head of this character wherein 30 in the destruction of the barrel after once being used is eliminated and at the same time avoids any repairing of the barrel while in constant use, the head being practically indestructible and can be fitted within 35 old or new barrels in a convenient manner.

A still further object of the invention is the provision of a head of this character which is extremely simple in construction, readily adaptable to and removed from a 40 barrel, strong, durable and inexpensive in manufacture and installation.

Other objects will be in part obvious and in part hereinafter set forth.

The invention accordingly consists in the 50 features of construction, combination of elements and arrangement of parts which will be exemplified in the construction herein-after described, and the scope of the appli-

cation of which will be indicated in the appended claim. 55

In the accompanying drawings:

Figure 1 is a fragmentary perspective view of an ordinary barrel showing the wooden head removed and adaptable for the reception of the self-locking barrel head constructed in accordance with the invention; 60

Fig. 2 is a top plan view showing the head applied; 65

Fig. 3 is a side elevation of the head removed from the barrel; 65

Fig. 4 is a bottom plan view of the head removed from the barrel; 70

Fig. 5 is a plan view showing the removable section of the head detached from the retaining rim; 70

Fig. 6 is a fragmentary vertical longitudinal sectional view through the barrel and head; 75

Figure 7 is a fragmentary sectional view on the line 7—7 of Fig. 2. 75

Similar reference characters indicate corresponding parts throughout the several views of the drawings.

Referring more particularly to the drawing, A designates a portion of an ordinary barrel which is made up of a plurality of barrel staves as usual, with the hoops applied, and at each end is formed the inner beveled surface B circumferentially of the body of the barrel, while next to this surface 80 interiorly of the latter is the groove C for the reception of the ordinary wooden head, and in lieu thereof is employed the self-locking head hereinafter fully described. 85

The self-locking head comprises an annular rim 10 preferably made from metal and is tapered correspondingly to the beveled surface B interiorly and at the end of the barrel, the rim being formed with an annular flange 11 out-turned therefrom at its outer edge to rest upon the open end edge of the barrel A, while the opposite edge of said rim B is formed with an annular inwardly extending flange 12 which forms a bearing or rest shoulder circumferentially of the rim 100 for a purpose presently described. 90

Struck outwardly from the body of the rim 10 intermediate the flanged edges there-of is an external rib 13 which is adapted to engage in the groove C interiorly of the 105 barrel A so that the rim 10 will be securely

fastened in place in the end of said barrel when it is forced or mounted therein so that the rim 10 will constitute a permanent part of the barrel until the same is destructed by 5 reason of excessive use thereof. It will be noted that this rim 10 materially reinforces the end of the barrel to avoid the breaking or crushing of the barrel or the displacement of any of the staves and thereby materially 10 strengthens said barrel at each end thereof to increase the life of the same, as will be apparent.

Removably held within the rim 10 is the head proper which comprises a disk 14 preferably made from metal, although the same may be made from any other suitable material having the required strength and rigidity and is designed to rest upon the flange 12 for closing the end of the barrel, the disk 20 14 being formed at intervals with substantially key-hole shaped slots 15 which are curvilinear in their length in correspondence with the peripheral edge of the disk 14 and are slightly spaced therefrom, while permanently 25 fixed in the flange 14 of the rim 10 at intervals are retaining lugs 16 which are formed with heads 17, and these lugs are adapted to engage in the slots 15, the heads being passed through the wider or other 30 ends thereof so that the lugs will pass into the narrow portions of the slots and the heads 17 will serve to retain the disk 14 within the rim, it being understood that the head is slightly rotated to permit the removal 35 or the retention thereof from and in the rim, and when retained therein will close the end of the barrel, as will be obvious.

Mounted on the disk 14 at diametrically opposite points are upstanding finger grips 40 18 and 19 respectively, the latter being formed with an aperture 20 to receive a sealing wire 21 which is also passed through an eye 22 formed on the heads of one of the lugs 16, and in this manner when the locking 45 seal is used the disk 14 can be secured in closing position and thus eliminate the surreptitious opening of the barrel during transit thereof. The lugs 18 and 19 serve to permit the turning of the disk 14 in the 50 rim for permitting the application of said disk or the removal thereof.

Mounted on the disk 14 at the desired point is a resilient catch 23 which works

through an opening 24 in said disk and also engages in an opening 25 in the flange 12 55 so that the disk 14 can be locked against turning movement when the retaining lugs are engaged in the narrow portions of the slots 15 for holding the disk 14 within the rim 10 to close the barrel. The resilient 60 catch 23 is formed with a finger-hold 26 so that it can be manually released to permit the quick removal of the disk 14 for the opening of the barrel. Connected to the rim 10 and to the inner face of the disk 14 is a chain 27 which is of the required length 65 and serves to prevent the separation of the disk 14 from said rim when the head is in use or disuse so as to avoid the accidental loss of either of the parts thereof. 70

From the foregoing description, taken in connection with the accompanying drawings, the construction and operation of the herein described barrel head will be readily apparent and, therefore, a more extended explanation has been omitted. 75

Having thus described our invention, we claim:

In a barrel constructed with the chine and groove for the head, a self locking head comprising an annular rim made from metal tapered correspondingly to the internal surface of the chine and engaged therewith and formed with an annular flange out-turned therefrom at its outer edge to overlap and rest against the end edge of the barrel, the rim being also provided with an inwardly extending annular flange forming a rest shoulder, a rib struck outwardly circumferentially from the rim intermediate the flanges for engagement in the groove in the chine to secure said rim in place, a disk forming a barrel head detachably engaged on the shoulder, and a spring catch carried by the disk and working through the same 95 for the automatic engagement thereof in the shoulder to lock said disk against movement thereon. 85

In testimony whereof we affix our signatures in the presence of two witnesses.

WILLIAM H. SHERMAN.
JOHN F. McGINNITEY.

Witnesses:

STEPHEN K. OWEN,
ROY O. LINDSAY.
